UNITED STATES PATENT OFFICE

JOHN N. THOMAS, OF BALTIMORE, MARYLAND, ASSIGNOR TO MAY OIL BURNER CORPORATION, OF BALTIMORE, MARYLAND, A CORPORATION OF MARYLAND

ADVERTISING DEVICE

Application filed November 11, 1930. Serial No. 494,929.

The present invention relates to improvements in advertising devices, and particularly to an advertising or display device for promoting sales of oil or other burners for heating furnaces.

According to the invention, a simple and inexpensive means is provided for the purpose of advertising an oil or other fuel burner for heating furnaces, which will simulate the interior of the fire box of a heating furnace representing the flame from the fuel burner.

In the accompanying drawings:

Figure 1 is a view in perspective of one form of advertising device.

Figure 2 is a view in perspective of a modified form of housing.

Figure 3 is a view in vertical section on substantially the line 3—3 of Figure 2, looking in the direction of the arrows.

Figure 4 is a view in horizontal section on substantially the line 4—4 of Figure 2, looking in the direction of the arrows.

Figure 5 is a view in vertical section on substantially the line 5—5 of Figure 3, looking in the direction of the arrows.

Referring to the drawings, in the several views of which like parts are designated by the same reference characters, A designates an oil or other fuel burning apparatus which includes a rotary fan or blower within a suitable housing, the outlet from which communicates with a blast conduit A'.

The display device of the present invention which is intended for use with a burner of the type referred to comprises a housing which may be made of any suitable material, which housing has the appearance of a more or less complete heating furnace.

One of the vertical walls 1 of the housing is provided with representations of the doors commonly provided on the fronts of such furnaces, such as a fuel supply door 2 and clean-out doors 3, and the portion of the front where the ash pit door is commonly located is closed by a plate 4, in which is formed an opening that receives the outlet or blast pipe A' of the burner A.

The housing also includes a side wall 10 in which is formed an opening 11, through which the interior of the housing may be per-

ceived. Preferably, the viewing aperture 11 is surrounded by inwardly directed flange-like members 12, which, as shown, are marked, as at 13, to have the appearance of a brick lining in the furnace.

A covering 14 of any suitable translucent material extends across the aperture 11.

If the housing comprises four vertical walls, it will be understood that apertures 11 may be formed in both of the side walls, and in any event, the housing is provided with a top or ceiling member 15 arranged in a plane above the inspection aperture or apertures 11, and so as not to be visible through said apertures.

A suitable outlet for air delivered into the casing is provided in one of the vertical walls or in the top, and this may, if desired, be in communication with a flue representing the smoke pipe of the furnace.

The walls of the housing may support water gauges, pressure devices, or other attachments such as usually found on heating furnaces or representations of such devices.

Within the housing is arranged a vertical screen 16 preferably made of fabric, and which may, if desired, be marked to represent, when properly illuminated, flames such as are produced by the combustion of fuel in the fire box of a furnace. This screen is supported at its top and bottom edges by being attached to parallel frame members 20, 21, but is not stretched taut except along its edge, which extends directly across the opening provided in the housing to receive the air blast conduit from the burner A, and when the fan or impeller of the burner is in motion, the currents of air directed against such free edge will cause the body of the screen to undulate, so that as viewed through the aperture 11, there is created a vivid representation of flames, such as are produced in the fire box of a furnace by the combustion of fuel.

Preferably the portion of the forward edge of the screen 16, which is directly in alignment with the opening for the air blast conduit is reinforced or stiffened by a suitable member 22, which, acted upon by the currents of air, causes practically the entire

screen to undulate from such reinforced section as a center.

In the lower portion of the housing, below the plane of the aperture, or apertures 11, is arranged a suitable means for illuminating the screen. As shown, this means comprises an electric lamp, or lamps, 25, the cable 26 from which leads to a suitable source of current.

10. It is not necessary that the housing be provided with a bottom as the lower edges of the vertical walls thereof can rest upon the floor of a display room, or, if preferred, upon any suitable base or support.

15. The screen 16 may be colored, or the requisite coloring may be produced by employing colored bulbs for the illuminating devices, or both these expedients may be employed.

20. It is believed that the advantages and manner of using the improvements will be readily understood from the foregoing description and the drawings.

25. The invention provides a very simple and inexpensive, but extremely effective means for showing the operation of fuel burners of the type referred to and makes a most attractive display.

30. Of course, there can be variation from some of the details shown without departing from the invention, and except as defined in the appended claims, the invention is not to be understood as limited to the exact details shown.

35. The term "housing" employed in the claims is intended to include any arrangement of vertical walls and a ceiling-like member, it being only necessary that two of the vertical walls represent, respectively, the front and a side of a heating furnace or portions thereof.

40. The housing may be made of any suitable material and the parts can be of knock-down construction, or so detachably connected that they can be folded or packed to occupy a relatively small space or be erected into the relations shown in the drawings.

45. It will be understood that the translucent covering 14 of the aperture 11 is such that while the screen within the housing is not clearly visible, yet an observer can perceive the undulations of such screen produced by the air blast and the appearance of flame will be simulated.

50. I claim:

1. In an advertising device, the combination of a housing simulating the appearance of the fire box portion of a heating furnace and provided with an aperture through which the interior thereof may be perceived and having in a vertical wall an aperture adapted to receive an air blast conduit, said housing having also an air outlet, a translucent closure for said perception aperture, a non-rigid screen within the housing having a

55. relatively taut edge exposed to air supplied through the blast conduit aperture, whereby the screen will be undulated by said air blasts, and means for illuminating the screen.

60. 2. In an advertising device, the combination of a housing, two of the vertical walls of which simulate respectively, the exterior of the front and a side wall of a heating furnace, the portion of the front representing an ash pit door having formed therein an opening adapted to receive an air blast conduit and the side wall being provided with an aperture, a translucent closure for the last said aperture, the housing having also an air outlet, a fabric screen positioned vertically within the housing with its front edge in the path of air supplied through said opening in the front wall, and means for illuminating the screen.

65. 3. In an advertising device, the combination of a housing, two of the vertical walls of which simulate respectively, the exterior of the front and a side wall of a heating furnace, the portion of the front representing an ash pit door having formed therein an opening adapted to receive an air blast conduit and the side wall being provided with an aperture, a translucent closure for the last

70. said aperture, the housing having also an air outlet, a non-rigid screen positioned vertically within the casing and supported throughout the length of its top and bottom edges with its free front edge in the path of air supplied through said opening in the front wall, and means for illuminating the screen.

75. 4. In an advertising device, the combination of a housing, two of the vertical walls of which simulate respectively, the exterior of the front and a side wall of a heating furnace, the portion of the front representing an ash pit door having formed therein an opening adapted to receive an air blast conduit and the side wall being provided with an aperture, a translucent closure for the last

80. said aperture, the housing having also an air outlet, a non-rigid screen positioned vertically within the casing and supported throughout the length of its top and bottom edges with its free front edge in the path of air supplied through said opening in the front wall, and means for illuminating the screen.

85. 5. In an advertising device, the combination of a housing, two of the vertical walls of which simulate respectively, the exterior of the front and a side wall of a heating furnace, the portion of the front representing an ash pit door having formed therein an opening adapted to receive an air blast conduit and the side wall being provided with an aperture, a translucent closure for the last

90. said aperture, the housing having also an air outlet, a non-rigid screen positioned vertically within the casing and supported throughout the length of its top and bottom edges with its free front edge in the path of air supplied through said opening in the front wall, and means for illuminating the screen.

95. 6. In an advertising device, the combination of a housing having in an end wall an opening adapted to receive an air blast conduit and having in a side wall an aperture through which the interior of the housing may be perceived, the housing being further provided with an opening for the escape of air therefrom, a translucent closure for the aperture in the side wall of the housing, a

non-rigid screen, provided with markings representing flames, supported within the housing with one edge extending vertically across the air blast conduit opening, and means for illuminating said screen.

6. In an advertising device, the combination with a housing simulating the appearance of a heating apparatus and having an opening adapted to receive an air blast conduit and in a side wall an aperture through which the interior of the housing may be perceived, the housing being further provided with an opening for the escape of air, a translucent closure for the aperture in the side wall of the housing, a fabric screen, provided with markings representing flames, supported within the housing and extending across the said opening in the side wall with an edge extending across the air blast conduit opening, and means for illuminating said screen.

7. In an advertising device, the combination of a housing, two of the vertical walls of which simulate respectively, the exterior of the front and a side wall of a heating furnace, the portion of the front representing an ash pit door having formed therein an opening adapted to receive an air blast conduit and the side wall being provided with an aperture, a translucent closure for the last said aperture, the housing having also an air outlet, a fabric screen positioned vertically within the housing with its front edge in the path of air supplied through said opening in the front wall, means for reinforcing the front edge of the screen in direct alignment with the opening for the blast air conduit, and means for illuminating the screen.

8. In an advertising device, the combination of a housing, two of the vertical walls of which simulate respectively, the exterior of the front and a side wall of a heating furnace, the portion of the front representing an ash pit door having formed therein an opening adapted to receive an air blast conduit and the side wall being provided with an aperture, a translucent closure for the last said aperture, the housing having also an air outlet, a fabric screen positioned vertically within the housing with its front edge in the path of air supplied through said opening in the front wall, and means within the housing below the plane of said aperture in the side wall for illuminating the screen.

9. In an advertising device, the combination of a housing, one vertical wall of which simulates the exterior of the front of a heating furnace, the portion of said wall representing an ash pit door having formed therein an opening adapted to receive an air blast conduit, the side walls of the housing being each provided with an aperture, a translucent closure for each of the last said apertures, a fabric screen positioned vertically within the housing with its front edge in the path of air

supplied through said opening for an air blast conduit, and means for illuminating both faces of the screen.

10. In an advertising device, the combination of a housing closed at the top and having one of its vertical walls simulating the exterior of a portion of the front of a heating furnace, a side wall of the housing having an opening formed therein, a translucent closure for such opening, a non-taut fabric screen arranged vertically within the housing and provided with markings representing flames, and means for illuminating said screen. 70

11. In an advertising device, the combination of a housing closed at the top and having one of its vertical walls simulating the exterior of a portion of the front of a heating furnace, a side wall of the housing having an opening formed therein, a translucent closure for such opening, a non-taut fabric screen arranged within the housing, means for illuminating said screen, and a fuel burner including a blower, the outlet of which extends through the wall of the housing simulating the front of the furnace for undulating said screen. 80

12. In an advertising device, the combination of a housing simulating exteriorly a furnace and provided with an aperture through which the interior thereof may be perceived and with an aperture to receive an air blast, a flange projecting inwardly from the edge of said aperture, a screen designed to give the effect of flame within the housing and perceptible through said aperture and so disposed as to be undulated by a blast of air through the blast aperture, and means for illuminating said screen disposed at one side of said flange and out of the normal line of vision through said aperture. 90

13. In an advertising device, the combination of a housing provided with an aperture through which the interior thereof may be perceived and with an aperture to receive an air blast, a screen within the housing perceptible through said aperture and so disposed as to be undulated by a blast of air through the blast aperture, and means to disperse the air currents so that they will act with substantial uniformity upon the screen. 100

14. In an advertising device, the combination of a housing provided with an aperture through which the interior thereof may be perceived and with an aperture to receive an air blast, a screen within the housing perceptible through said aperture and so disposed as to be undulated by a blast of air through the blast aperture, and means carried by said screen to disperse the air currents so that they will act with substantial uniformity upon the screen. 110

In testimony whereof I have hereunto set my hand.

JOHN N. THOMAS. 130
